MATERNITY GARMENT

Berdie Smink, New York, N. Y.

Application September 8, 1939, Serial No. 293,993

3 Claims. (Cl. 2—211)

This invention relates generally to garments and more particularly it relates to maternity garments.

Among the characteristics desirable in a maternity garment are neatness of appearance and comfort, and the provision of a garment having these characteristics and also the characteristics of strength, convenience and economy are among the general objects of my invention.

Among the more particular objects of my invention is the provision in a maternity garment adapted to surround the abdominal portions having a waist encircling portion of a pair of flaps that overlap each other and have means on the waist-engaging portions thereof whereby they may be secured in various positions of adjustment to accommodate various girths.

A further object of the invention is the provision in a garment provided with flaps, as hereinabove described, of a front panel having a movable portion adapted to cover the aforementioned flaps and thereby to produce a neat-appearing garment, and further the provision in a garment as just described of a panel having a movable portion provided with a waist encircling portion.

Among the objects of my invention is further the provision in a garment having overlapping waist-engaging flaps of roughened surfaces on the contacting portions of said flaps.

To attain these objects and such further objects as may appear herein or be hereinafter pointed out, I make reference to the accompanying drawings, forming a part hereof, in which:

Figure 1 is a fragmentary perspective view of a skirt embodying my invention as viewed from the front;

Figure 2 is a view similar to Figure 1 but showing the parts in opened or partly opened position;

Figure 3 is a perspective view from the side of the skirt of Figure 1;

Figure 4 is a fragmentary perspective view, similar to Figure 1, of a second embodiment of my invention;

Figure 5 is a view similar to Figure 4 showing the front panel of the skirt in open position;

Figure 6 is a fragmentary view similar to Figure 4 of a modified form.

In Figures 1, 2 and 3, I have shown a maternity skirt consisting of two portions, a rear portion 10 and a front portion, designated collectively by the numeral 11, and shown as constituted by sections or panels 12, 13 and 14 joined together in any suitable or preferred manner. Obviously also the rear portion 10, shown as in

one piece, may be similarly constituted of sections if desired.

The portions 10 and 11 are shown joined together in any suitable or preferred manner, as by 5 seams 15 and 16, and it will be observed that these seams extend only part of the way up from the bottom, so that adjacent the waist-line the portions 10 and 11, at an intermediate point just below the hip line, are not joined together and 10 leave a covering flap 20. Extending forwardly from each side of the portion 10 are a pair of flaps 17 and 18, shown as of generally triangular conformation and of such length and conformation that they are adapted to encircle the waist 15 of a wearer and overlap each other. Means are provided for securing the flaps 17 and 18 together in various positions of adjustment, whereby the garment will accommodate itself to various waist girths. Such means may be of any suitable 20 character which will hold the flaps 18 and 19 in overlapping, and preferably co-terminus position at the waist band. I have illustrated the clasp fasteners shown in the drawings arranged at equally spaced positions, having the female 25 portions 19a on the flap 17, and the male portions 19b on the flap 18, and which latter are arranged at correspondingly equal spaces.

The overlapping surfaces of the flaps 17 and 18 are preferably of such character that they 30 will resist any tendency for the flaps to slide over each other and sag from the normal waist line portion. For this purpose the frictional characteristics of woolen fabrics accentuate the binding and tying action which will be further 35 accomplished where the fabric is brushed fabric, such as cheviot, or of cheviot finished fabric. The covering flap 20 cooperates with the overlapping position of the flaps 17 and 18 to accentuate further interacting binding action to 40 carry out the objective of preventing sagging of the garment from the waist line position. The features of this construction will be understood to preserve the predeterminedly designed cut or form of the skirt portion of the garment.

45 It will be observed that flaps as described will provide a strong construction that will not give readily and that may be adjusted to suit all ordinary requirements. It is to be noted that this construction is greatly superior to constructions using lacing, since there is no tendency for the flaps to cut into the flesh, which is the case with lacing.

The upper part of the front portion 11 constitutes a flap, designated by the numeral 20 (see Figures 2 and 3) which in its normal po-

sition, as shown in Figure 1, covers the flaps 17 and 18 and gives the garment a neat appearance. To hold it in place I have shown means in the form of bands 23 and 24 that are adapted to encircle the waist and to be tied together.

Additional support for the flap 20 may be provided in the form of means such as clasp fasteners comprising complementary parts 21 and 22 carried respectively by the flaps 17 and 20. However, since as the girth of the wearer increases, the flap 20, where it is connected to the flap 17 by these fasteners, cannot accommodate itself to this increased girth, the use of the fasteners may be dispensed with, and reliance placed only on the bands 23 and 24.

The surface of the flap 20 where it overlaps the flap 17, is also preferably rough or roughened, and the remarks anent this feature in flaps 17 and 18 apply to the flap 20 as well.

It will be seen that I have provided a construction that has supporting and bracing action coupled with neat appearance, and that is readily and conveniently donned as well as discarded.

Referring now to Figures 4 and 5, which show a second embodiment of my invention, the skirt shown therein comprises a frusto-conical body portion 30 almost completely encircling the limbs of a wearer, but falling short thereof at its front lower portion so as to leave a gap. However the upper portions of the body 30 are extended into flaps 31 and 32 that are adapted to encircle the waist of a wearer and to overlap and correspond in function to the flaps 17 and 18 of the first embodiment. They may be secured together by suitable means such as the clasp fasteners shown at 33 in the drawings.

The aforementioned gap at the lower front of the body portion 30 is closed by a pleated panel 34 secured to the body portion at its sides, the pleating being indicated at 34a, and shown depending from a portion 35 extending upwardly to the waist line and provided with a pair of lateral flaps 36 and 37. The said portion 35 together with its flaps 36 and 37 is adapted to overlie the flaps 31 and 32 so as to conceal them and it may be attached to the flap 31 by suitable or preferred means such as the clasp fasteners shown in the drawings, which have complementary portions 38 and 39 carried respectively by the portion 35 and its flaps 36 and 37 on the one hand, and the flap 31 on the other. Bands 40 and 41 attached to the ends of the flaps 36 and 37 respectively serve for encircling the waist and for holding the flaps 36 and 37 in place.

From Figure 5 it clearly appears that the portion 35 with its flaps 36 and 37 may be folded down so as to expose the flaps 31 and 32, which may then be unfastened. The construction is therefore similar to that of Figures 1, 2 and 3. Its advantages lie in the use of the pleated panel 34, which permits of expansion when desired, while normally hanging with its parts overlapping and therefore giving the skirt a relatively slim appearance.

In the modification shown in Figure 6, the construction is similar to that shown in Figures 4 and 5 except that the pleating 34a has been omitted. The parts of this modification have been designated by the numerals used for corresponding parts in the embodiment of Figures 4 and 5, these numerals however being primed. At 42 and 43 I have shown the seams that join the panel 34' to the body portion 30'.

It will be understood that all parts of the gar-

ments disclosed herein may be made of more than one piece, such pieces being joined together, and on the other hand, where a part is shown as made in several pieces (as the part 11 for example) that it may, where no functional advantage is lost by the pieced construction, be made in one piece.

Referring again to the first embodiment, that is, the embodiment of Figures 1, 2 and 3, it will be observed that the clasp fastener portions 19a are arranged at uniformly spaced intervals adjacent the upper edge of the flap 17. Similarly, the clasp fastener portions 19b, complementary to the portions 19a, are arranged at uniformly spaced intervals adjacent the upper edge of the flap 20. The spacing of the portions 19a is identical with that of the portions 19b, so that the portions 19a and 19b register along the entire upper edge of the overlapping portions of flaps 17 and 18. As a result of this construction a distributed fastening is obtained in which all the fastener portions 19a and 19b may be in simultaneous engagement throughout the extent of the overlapping portions of the flaps 17 and 18.

It will consequently be seen that the waist girth as predetermined by flaps 17 and 18 is adjustable by increments, and the length of each increment is equal to the distance between adjacent clasp fasteners. For each position of adjustment, the fastening uniting the flaps 17 and 18 will be distributed along the upper edges of their overlapping portions. The advantages of such a distributed fastening in preventing sagging and bulging, as opposed to a fastening in which only a few, or even only one fastener, are used, are almost too obvious to require mention. It will be understood also that maintaining the waist line against sagging, as accomplished by the features I have disclosed, preserves the design of the skirt at the hips and waist so that a predeterminedly fashioned skirt is not objectionably altered.

The fineness of adjustment is dependent on the distance between adjacent fasteners; obviously, greater fineness may be obtained by making this distance smaller.

These remarks also apply to the fasteners 33 and 33' of the other embodiments.

Since the flaps 17 and 37 are always secured together in the same relationship, the spacing of their fasteners need not be as close as that of the fasteners 19a and 19b because, although a distributed fastening is desired, no provision need be made for relative adjustment. The same remarks apply to the corresponding parts of the other embodiments.

It will now be clear that I have provided a garment construction that is simple, effective and economical, and presents a neat appearance while giving the desired support to the abdominal portions, and while affording convenience in the putting on or removal of the garment.

It is to be understood that the various parts of the garments herein disclosed are not intended to be used only in the exact relationship shown, but that my invention also contemplates their use in other relationships and combinations. It is furthermore to be understood that while I have described my invention in its application to skirts, and in particular to maternity skirts, that it may be used for other types of garments, and for garments other than maternity garments.

While I have herein disclosed several illustrative embodiments of my invention, it will be un-

derstood that the same may be embodied in many other forms without departing from the spirit thereof, as will be obvious to those skilled in the art, and that the disclosure herein is by way of illustration merely and is not to be interpreted in a limiting sense, and that I do not limit myself other than as called for by the language of the appended claims.

Having thus described my invention and illustrated its use, what I claim as new and desire to secure by Letters Patent is:

1. A maternity skirt having a rear panelled portion formed to provide a form-fit adjacent the rear of the garment and extending forwardly into communicating engagement with a front panelled portion at a portion substantially below the hip line and at substantially the lateral sides of the garment and having sections directed towards each other substantially above the hip line, separated and independently adjustable from the front panelled portion adjacent a point of the lateral sides of the garment and having extensions from said sections providing waist band members extended towards each other into overlapping positions in the direction of the waist line, the front panelled portion adjacent the hip line being connected to the forwardly directed sections of the rear panelled portion from points rearwardly from the terminal edges thereof at substantially the lateral sides of the garment and being separated and formed substantially above the hip line with sidewardly extending flaps which terminate in ties extended to encircle the waist line and provide a variable waist-line suspension for said front panelled portion, said waist band members each being provided with fastener members having complementary engaging connections on said respective band members whereby said band members may be positioned in adjustable relationship with each other and cooperating with the front panelled portion and the overlying flaps thereof above the hip line to maintain the sections suspended from the waist line at the frontal portions of the garment.

2. A maternity skirt having a rear panelled portion formed to provide a form-fit adjacent the rear of the garment and extending forwardly into communicating engagement with a front panelled portion at a portion substantially below the hip line and at substantially the lateral sides of the garment, which front panelled portion is arranged normally to lie in folds adapted to expand circumferentially and having sections directed towards each other substantially above the hip line, separated and independently adjustable from the front panelled portion adjacent a point of the lateral sides of the garment and having extensions from said sections providing

waist band members extended towards each other into overlapping positions in the direction of the waist line, the front panelled portion adjacent the hip line being connected to the forwardly directed sections of the rear panelled portion from points rearwardly from the terminal edges thereof at substantially the lateral sides of the garment and being separated and formed substantially above the hip line with sidewardly extending flaps which terminate in ties extended to encircle the waist line and provide a variable waist-line suspension for said front panelled portion, said waist band members each being provided with fastener members having complementary engaging connections on said respective band members whereby said band members may be positioned in adjustable relationship with each other and cooperating with the front panelled portion and the overlying flaps thereof above the hip line to maintain the sections suspended from the waist line at the frontal portions of the garment.

3. A maternity skirt having a rear panelled portion formed to provide a form-fit adjacent the rear of the garment and extending forwardly into communicating engagement with a front panelled portion at a portion substantially below the hip line and at substantially the lateral sides of the garment and having sections directed towards each other substantially above the hip line, separated and independently adjustable from the front panelled portion adjacent a point of the lateral sides of the garment and having extensions from said sections providing waist band members extended into overlapping positions in the direction of the waist line, the front panelled portion adjacent the hip line being connected to the forwardly directed sections of the rear panelled portion from points rearwardly from the terminal edges thereof at substantially the lateral sides of the garment and being separated and formed substantially above the hip line with sidewardly extending flaps which terminate in ties extended to encircle the waist line and provide a variable waist-line suspension for said front panelled portion, said waist band members each being provided with a plurality of equi-distantly spaced fastener members having complementary engaging connections on said respective band members whereby said band members may be positioned in adjustable relationship with a plurality of said complementary fastener members in engagement with each other and cooperating with the front panelled portion and the overlying flaps thereof above the hip line to maintain the sections suspended from the waist line at the frontal portions of the garment.

BERDIE SMINK.
